CLAIM

Applicants claim the ornamental design for a cap hood, as shown and described.

DESCRIPTION

FIG. 1 is a perspective view of the cap hood, shown on a cap.

FIG. 2 is a top view of the cap hood shown in FIG. 1.

FIG. 3 is a bottom view of the cap hood shown in FIG. 1.

FIG. 4 is a left side view of the cap hood shown in FIG. 1.

FIG. 5 is a right side view of the cap hood shown in FIG. 1.

FIG. 6 is a front view of the cap hood shown in FIG. 1; and,

FIG. 7 is a rear view of the cap hood shown in FIG. 1.

The broken lines in the drawing figures showing a cap illustrate environmental matter and form no part of the claimed design.
